UNITED STATES PATENT OFFICE.

HARRY B. COX, OF CINCINNATI, OHIO.

ELECTRO-MECHANICAL WHISTLE.

SPECIFICATION forming part of Letters Patent No. 352,044, dated November 2, 1886.

Application filed July 13, 1886. Serial No. 207,943. (No model.)

To all whom it may concern:

Be it known that I, HARRY B. COX, of Cincinnati, in the county of Hamilton and State of Ohio, have invented certain new and useful 5 Improvements in Electro-Mechanical Whistles; and I do hereby declare that the following is a full, clear, and exact description of the invention, which will enable others skilled in the art to which it appertains to make and use 10 the same, reference being had to the accompanying drawings, and to the letters of reference marked thereon, which form part of this specification.

My invention relates to whistles such as are 15 used on locomotives, stationary and marine engines, fog-horns, and air-whistles; and it has for its object to furnish a novel mechanism for operating such whistles.

With this object in view my invention consists in the improved construction, arrangement, and combination of parts hereinafter 20 fully described, and afterward specifically pointed out in the claims.

In the accompanying drawings, Figure 1 is 25 a view in perspective of the whistle and operative mechanism complete. Fig. 2 is a view of the upper portion of the whistle, partly in section and partly in side elevation; and Fig. 3 is a view in side elevation of the valve-plug 30 detached.

Like letters of reference mark the same parts in all the figures.

Referring to the drawings by letters, A is 35 an ordinary steam or compressed-air whistle, provided with a valve to admit the operative fluid. B is the casing of said valve, provided with an induction port or passage, b. C is the valve-plug, fitted accurately in the casing B, and provided with small ends c, which project 40 through the packing-glands b" of the casing B. The valve-plug is provided with an elongated slot of substantially rectangular section. The induction-passage b of the casing is of the same section. The induction-passage b', however, is of the ordinary shape, being circular 45 in section, and tapering to concentrate the fluid before reaching the whistle.

D is the supporting-upright, serving also as the pipe to conduct the steam or air from 50 supply-pipe E to the whistle.

F are levers secured to the ends c c of

valve-plug C, while their lower ends are pivotally secured at f f to rod G, which in their turn have a cross-bar, H, loosely pivoted in their outer ends, as at g g. On the center of 55 the cross-bar G is secured one end of an armature, I, which is pivoted in brackets or lugs I', projecting from the support D, and at its opposite end engages an electro-magnet, J, the armature being kept normally in its disengaged position by a spring, i, and being regulated as to extent of throw by a set-screw, i'.

K are wires from the battery.

The mechanism is operated as follows, viz: The circuit being open, the armature by virtue of the spring i will remain in its outer position at the lower end, out of contact with the magnet J, in which position the valve will be closed. To open the valve and sound the whistle, it is only necessary to close the circuit 70 in any well-known manner, or by any suitable circuit-closer, when the electro-magnet, becoming active, will draw the lower end of the armature to it, and as a consequence its upper end will be moved outward, which motion, 75 through the medium of rods or links G and levers F, will turn the valve-plug so that the induction-passage of the valve and the slot of the valve-plug will coincide, thus allowing a free passage for the fluid to the whistle. But a 80 very small movement of the plug is necessary, due to the shape of the slot in it and the induction-passage. These being elongated, may be made very narrow without unnecessarily curtailing their area, and a movement of about 85 one-eighth of a revolution will fully open or close the valve, whereas nearly a half-revolution would be necessary with these openings of a circular area.

The special advantages claimed for this invention, of the combination of valve-whistle and electro-magnet, and the uses to which it is applicable, are, first, if used in connection with an electric-bell cord or signaling device on railroad trains, it has the advantage over 90 an ordinary electric gong in that the motion and jar of the train does not make it jingle or tend to throw it out of order, as is invariably the case with an electro-gong; second, if used as an alarm-signal on marine engines, it can 95 be operated by a push-button from any part of the vessel at which said button is located;

third, it gives, when used as above cited, a much clearer and louder signal; fourth, when, as an alarm-signal on stationary engines, push-buttons may be placed at convenient places, 5 and in case of an accident to the machinery an instant and loud signal can be given the engineer; fifth, its especial advantage is that when steam or compressed air can be used it gives a louder and clearer signal than can be 10 made by any known contrivance operated by electro or electro-mechanical means.

Having thus fully described my invention, what I claim as new, and desire to secure by Letters Patent, is—

15 1. In combination, a whistle, its valve having a suitable casing with elongated induction-passage and circular eduction - port, and a valve-plug with an opening corresponding in section with the induction-passage, as set forth.

2. The combination, with the whistle, the 20 magnet, and its armature, of the valve having casing B, with the induction-passage b, elongated in section, and eduction-port circular and tapered, valve-plug having opening c', corresponding with the induction - passage b, 25 and ends c e, and the levers and rods connecting the valve-plug with the armature, as set forth.

In testimony that I claim the foregoing as my own I affix my signature in presence of two 30 witnesses.

HARRY B. COX.
